DESIGN FOR A SHIRTBAND AND COLLAR SUPPORT

David A. Gordon, New York, and Joseph Cohen,
Brooklyn, N. Y.

Application June 30, 1944, Serial No. 114,262

Term of patent 3½ years

(Cl. D80—5)

To all whom it may concern:

Be it known that we, David A. Gordon and Joseph Cohen, both citizens of the United States, residing at New York and Brooklyn, New York, respectively in the counties of New York and Kings, respectively, and both in the State of New York, have invented a new, original, and ornamental Design for a Shirtband and Collar Support, of which the following is a specification, reference being had to the accompanying drawing, forming a part thereof.

In the drawing:

Fig. 1 is a plan view of a short band and collar

support in its unfolded position showing our new design;

Fig. 2 is a front perspective view of the support in folded position with the cut-out portion in Fig. 1 raised; and

Fig. 3 is a rear perspective view thereof with the cut-out portion in lowered position.

We claim:

The ornamental design for a shirtband and collar support, as shown.

DAVID A. GORDON.
JOSEPH COHEN.
